2 SHEETS-SHEET 2.

UNITED STATES PATENT OFFICE.

FRANK EZRA SUMMERS, OF MEMPHIS, MISSOURI.

TELEPHONE SYSTEM.

1,106,592.

Specification of Letters Patent. Patented Aug. 11, 1914.

Application filed June 22, 1912. Serial No. 705,296.

To all whom it may concern:

Be it known that I, FRANK E. SUMMERS, citizen of the United States, residing at Memphis, in the county of Scotland and State of Missouri, have invented certain new and useful Improvements in Telephone Systems, of which the following is a specification.

My invention relates to new and useful 10 improvements in telephone systems, and the object of my invention is to provide a telephone system by means of which a subscriber may ring or talk in one direction only or in both, as preferred.

15 A further object of my invention is to provide a telephone system including a plurality of stations and line sections connecting each station with the stations next adjacent upon either side, the wiring and 20 switches being so arranged that the subscriber may cut the line in such a manner as to prevent all communication from stations at one side of the line, while receiving communications from the other side.

25 A further object of my invention is to so wire the system that when talking upon one section, the signaling mechanism is always in circuit with the other section.

With these and other objects in view, my 30 invention will be more fully described, illustrated in the drawings, and then specifically pointed out in the claims which are attached to and form a part of this application.

35 In the drawings: Figure 1 is a diagrammatic view of my improved telephone system, two stations being shown; Fig. 2 is a front elevation of the device which is attached to the ordinary telephone to accomplish the objects set forth above, the wiring 40 of the device being shown diagrammatically; Fig. 3 is a fragmentary front elevation of a telephone instrument, showing my device applied thereto; Figs. 4 and 5 are 45 fragmentary sectional views on the lines 4-4 and 5-5 of Fig. 2, showing details in the construction of the switch employed in my device.

Corresponding and like parts are referred 50 to in the following description and indicated in all the views of the drawings by the same reference characters.

The preferred embodiment of my invention includes a base or support 10, which is 55 preferably formed of wood, and which is secured in the manner shown, to the side of

a conventional telephone instrument having a receiver hook 12 which extends beneath the lower end of the support when the latter is in place. Secured to the upper end 60 of this support, are binding posts 13 and 14 to which the line wires are attached, as will be hereinafter more fully explained, and binding posts 15 and 16 from which conductor wires lead to the telephone instrument and to the calling mechanism, as will 65 also be explained. Electrically connected to the binding posts 13 and 14, is a lightning arrester 17 of the usual or any preferred type.

Mounted upon the support 10, is a knife 70 switch, designated as a whole by the numeral 18 and including contact members 19 and 20 and the pivoted blade 21. The contact member 19 includes a metallic plate 22 secured to the support 10 and a second metallic plate 23 hingedly secured by its lower 75 end to the plate 22. The free end of this second plate is perforated to receive a set screw 24 which passes through the plate, through the end of the blade 21 of the 80 switch, through the plate 22 and into the support 10. A helical spring 25 surrounds this set screw bearing between the head of the screw and the plate 23. By this means, the knife blade of the switch is pivotally 85 mounted between the plates 22 and 23 and frictionally engaged therebetween by the tension of the spring 25.

The contact member 20 includes plates 26 and 27, hinged together in like manner, the 90 free end of the plate 27 being bent outwardly into spaced relation to the plate 26, as shown, to provide for the reception of the blade 21 of the switch, the plates being held yieldably 95 into engagement with each other by a set screw 28 and spring 29. This switch is normally maintained in closed position by means of a helical spring 30, one end of which is secured to the switch blade and the other end of which is secured to a screw 31 100 carried by the support 10. The free end of this switch blade extends a considerable distance beyond the contact member 20 and is cut-away to form a shoulder 32 which, when the switch is opened, is engaged by the 105 downwardly depending hook 33 of an automatic catch 34 having a weighted end 35 which causes it to swing into engagement with the switch blade. This switch is manually opened when the telephone is being used 110 and in order to provide means for automatically closing the switch upon the hanging

up of the receiver, I have provided a link 36 provided adjacent its upper end with a longitudinally extending slot 37 through which is passed a pin 38 carried by the 5 switch blade 21. The lower end of this link 36 is shaped as at 39 to engage loosely about the shank of the receiver hook in such a manner that when the switch 21 is closed and the receiver hook is down, the hook 10 will bear against the lower side of the loop 39 while when the receiver hook is up, the switch still being closed the hook will bear against the upper side of the loop. It will therefore be seen that when the link 36 is 15 manually raised to open the switch 18, the receiver being off the hook, and the hook consequently in raised position, the receiver hook will seat in the lower end of the slot 40 of the link. The link is provided in- 20 termediate its length with a knob 41 by means of which it may be readily moved and its upper end with spaced pins 42.

The catch 34 is provided with a forwardly directed arm 43 which bears between the 25 pins 42, as shown, in such a way that upon the raising of the link to open the switch, the catch 34 is automatically swung into position to engage with the switch blade. Upon the returning of the receiver to its 30 hook, a downward movement of the hook immediately draws the link down and the uppermost of the pins 42 engaging against the arm 43 of the catch swings the latter out of engagement with the switch blade 35 permitting the spring 30 to close the switch. The slot 37 in the link permits the necessary downward movement of the link 36 independent of the switch blade to cause the release of the catch 34.

40 Mounted upon the support 10, preferably below the switch 18, is a double pole changing switch 44 including the swinging switch blades 45 and 46 connected by an operating handle 47 and pivoted to contacts 48 and 49. The free ends of these switch blades engage with the contacts 50 and 51 or the contacts 51 and 52, dependent upon the position of the switch.

A conductor wire 53 connects the binding 50 post 13 with the contact 20 of the switch 18, while the conductor wire 54 connects the binding post 14 with the contact 19 of said switch. A conductor wire 55 connects the contact 20 of the switch 18 with the 55 contact 50 of the pole changing switch, and a conductor 56 connects the contact 22 of the switch 18 with the contact 51 of the pole changing switch, while a conductor wire 57 connects the contacts 50 and 52 of the pole 60 changing switch. A conductor wire 58 connects the contact 49 of the pole changing switch with the binding post 15, while a conductor wire 59 connects the contact 48 of the pole changing switch with the binding 65 post 16.

Referring more specifically to the dia- 70 grammatic view of the telephone system, shown in Fig. 1 of the drawings, in which A and B indicate adjacent stations upon the line and C the sections of line wire connecting the stations, the operation of my system will be more clearly understood. In this view a suitable signal device, shown in the form of an electrically operated bell, is 75 designated by the numeral 60 and is associated with each instrument. This bell has one pole grounded as at 61, while its other pole is connected by a conductor wire 62 to a conductor wire 63 leading from the binding post 15 of my attachment to a receiver 80 hook operated switch.

The receiver arm 12 is swingingly mounted in the usual manner and pivoted to this arm, intermediate its length, is a rod 64 to which are pivotally connected the free ends 85 of a plurality of pivoted switch bars 65, 66 and 67, each of which forms one member of a switch, the other members of which consist of contacts 68, 69 and 70, respectively. These switches are so arranged that when the receiver is upon the hook, the switch bar 65 is in operative position, while the remaining switch bars are inoperative, while when the receiver hook is raised, the switch bar 65 is inoperative and the switch bars 66 and 67 are in operative position. 90

The conductor wire 63 from the binding post 15 is connected to the switch bar 65, while a conductor wire 71 connects the contact 68 with one of the line wire sections C. 100 The conductor wire 72 connects the binding post 16 with the contact 69, while the conductor wire 73 connects the switch bar 66 with one terminal of the secondary coil 74 of the induction coil 75, the other terminal 105 of which is connected by the conductor wire 76 to one of the binding posts of the receiver 77, the other binding post of which is grounded, as at 78.

A conductor wire 79 connects the switch 110 bar 67 with the transmitter 80, while a conductor wire 81 connects the transmitter with a terminal of the primary coil 82 of the induction coil, the other terminal of which is connected with a suitable source of electrical energy 83 by a conductor wire 84. A conductor wire 85 connects the battery or other source of energy 83 with the contact 70. Each instrument is also provided with a suitable calling device comprising a magnetic-generator 86, one pole of which is connected by a conductor wire 87 with the conductor wire 72, while its other pole is grounded as at 88. 115

In operation, assume that at all of the 120 stations the receivers are upon their hooks and the switches 18 closed. It will be seen that the line is closed at each station not only through the switch 18, but also providing the switch 44 is in the lefthand posi- 125 130

tion, through the switch 65. Now if any party on the line operates the generator 86, it will be evident that all of the call bells of the different instruments will be operated.

5 For the purpose of explanation, let it be assumed that station A calls station B. The party at station B upon hearing the signal removes his receiver from the hook, thereby opening the switch 65 and responds to the 10 party at station A who has also removed his receiver opening the switch 65 at that station. It will be seen that the operation of the system is identical with its customary use and that other parties upon the line may 15 call or listen over the line in the usual manner. Suppose however, that upon removing the receivers from the hooks, the parties at the stations also open the switches 18. It will be apparent that all stations, other 20 than those between stations A and B, will be cut out and will be unable to hear what is being said over the wire. It will therefore be seen that for adjacent stations this system will furnish absolutely private communication. 25 In this latter case it is necessary that the person being called swing the pole changing switch 44 from one side to the other to determine from which direction the call is coming. For instance, supposing 30 the pole changing switch 44 of station B was bridging the contacts 49, 50 and 48, 51, respectively, when station A called; the current of the talking circuit set up in the secondary coil 74 of station A would pass 35 through the receiver hook controlled switch 66, conductor 72, contacts 48, 51, conductor 56, and conductor 54 of station A, line C, conductor 53, conductor 55 and contacts 49, 50 of station B, and would not 40 pass to the receiver of the telephone instrument at station B. The party at said station upon listening would therefore find that he was not connected upon the line and would swing the pole changing switch to the 45 position shown, when the current would pass from the contact 50 through the conductor 57, through the contacts 48, 52, conductor 59, conductor 72 and switch 69.

With a system of this type, which absolutely cuts out all stations other than those in connection with each other and stations between such stations, it is absolutely essential that other stations be able to call those stations which are in communication in case 55 of extreme necessity and so get permission to use the line. I have provided for this by so arranging the pole changing switch and the wiring of the signaling mechanism that when stations are talking over one line section their signaling mechanisms are in circuit over the other line section. For instance, assuming that A and B are in communication with each other and the station to the right of A wishes to get the line. If 60 the generator is operated, the current will

pass over the line section C, conductor 53, conductor 55, contacts 49 and 50, conductor 58 and conductor 62 of station A to ring the bell at said station and so indicate that another party desires to use the line. The operator at station A can then either ring off or else swing his pole changing switch to bring himself in communication with the calling station to find out whether the matter is important or not. In like manner, 70 stations to the left of station B can call station B, although any stations between the two cannot call either station unless its switch 18 is closed.

As will be readily apparent, it is of the greatest importance that the switches 18 shall be closed when the stations are not in communication, as otherwise certain stations on the line would be cut out of communication. It is for this reason that I have provided the link connection between the receiver hook and the switch 18. It is also for this reason, in order to absolutely insure the effective closing of the switch, that I have provided the spring 30 to close the switch, 85 thus doing away with any imperfect closing of the switch, such as might be the case if its closing were dependent wholly upon the weight of the receiver upon its hook.

From the foregoing description, it will be apparent that I have provided a simple and effective telephone system, and one which may be adapted for use with the various forms of systems now in use with but slight modifications. The link 36 is preferably 90 formed in two parts which are insulated from each other to prevent the current passing from the switch blade 21 to the receiver hook 12. Also in practice the entire device is preferably covered by a suitable casing 95 having slots through which the handle of the pole changing switch and the knob of the link 36 project. This casing, for the sake of clearness, has been omitted from the drawings. It will further be noted that the generator is always in the talking circuit and a person can therefore call in the direction in which he wishes to talk after the switch 18 is opened and the open switch 18 will not permit the signals being transmitted in the 100 opposite direction, the calling to a certain extent being therefore selective.

It will be understood that the entire device may be inclosed within the casing of the telephone instrument proper if desired, suitable slots for the passage of the switch operating handles being provided therein.

Having thus described the invention, what is claimed as new is:

1. In a telephone system, the combination 125 with a plurality of telephone instruments, each including a receiver and receiver hook, a transmitter and a signaling mechanism, of a line including sections leading from one instrument to the next, and means for con- 130

necting the receiver and transmitter in circuit with one section of the line and the signaling mechanism in circuit with the opposite line section, said means including means 5 movable manually to active position after release of the receiver hook and automatically movable to inactive position upon depression of the hook.

2. In a telephone system, the combination 10 with a plurality of telephone instruments, each including a receiver and receiver hook, a transmitter and a signaling mechanism, of a line including sections leading from one instrument to the next, and means for selectively connecting the receiver and transmitter in circuit with either line section and the signaling mechanism in circuit with the opposite line section, said means including means manually movable into active position 15 after release of the receiver hook and automatically movable into inactive position 20 upon depression of the hook.

3. In a telephone system, the combination 25 with a plurality of telephone instruments, each including a receiver, a transmitter, and a signaling mechanism, of a line including sections leading from one instrument to the next, a switch normally connecting the line sections, conductors leading from said switch 30 to the instrument, and a pole changing switch included in said conductors.

4. A telephone system including a plurality of telephone instruments, a switch carried by each instrument, line sections connecting the switches of each instrument with the switches of adjacent instruments, conductors connecting the switch of each instrument with its instrument, and means releasable upon the depression of the receiver hook of the instrument for automatically closing said switch.

5. In a telephone system, the combination 45 with a line divided into sections, of a telephone instrument located between adjacent sections and including a transmitter, a receiver, a receiver hook and a signaling mechanism, all normally in circuit with both sections when the receiver hook is free, and means for opening the circuit between the 50 transmitter and receiver and one of the sections and between the signaling mechanism and the other section.

6. In a telephone system, the combination 55 with a line divided into sections, of a telephone instrument located between adjacent sections and including a transmitter, a receiver a receiver hook and a signaling mechanism, all normally in circuit with both sections when the receiver hook is free, and 60 means for simultaneously opening the circuit between the receiver and transmitter and either one of the sections and between the signaling mechanism and the other section.

7. In a telephone system, the combination 65 with a line divided into sections, of a tele-

phone instrument located between adjacent sections and including a transmitter, a receiver a receiver hook and a signaling mechanism, all normally in circuit with both sections when the receiver hook is free, 70 means for opening the circuit between the receiver and transmitter and one of the sections and between the signaling mechanism and the other sections, and means for reversing said open circuits.

8. In a telephone system, the combination 75 with a line divided into sections, of a telephone instrument located between adjacent sections and including a transmitter, a receiver a receiver hook and a signaling 80 mechanism, all normally in circuit with both sections when the receiver hook is free, means for opening the circuit between the receiver and transmitter and one of the sections and between the signaling mechanism 85 and the other section, and means operable by the depression of the receiver hook of the instrument for closing said open circuits.

9. In a telephone system, the combination 90 with a plurality of telephone instruments, each including a receiver, a transmitter and a signaling mechanism, of a line including sections leading from one instrument to the next, a switch normally connecting the line sections exterior to the instrument, conductors leading from said switch to the instrument, a pole changing switch included in said conductors, and means operable by the depression of the receiver hook of the instrument for automatically closing said 95 first mentioned switch.

10. In a telephone system, the combination 100 with a plurality of telephone instruments, each including a receiver, a receiver hook, a transmitter and a signaling mechanism, of a line including sections leading from one instrument to the next, a switch normally connecting the line sections, a pole changing switch, conductors leading from the first switch to the pole changing 110 switch, conductors leading from the pole changing switch to the instrument, means for normally holding the first mentioned switch in closed position; and means for holding said switch when in raised position.

11. In a telephone system, the combination 115 with a plurality of telephone instruments, each including a receiver hook, of a line including sections leading from one 120 instrument to the next, switches normally closing the line circuit at each instrument, conductors leading from said switches to the instruments, and including pole changing switches, means for holding the first mentioned switch when in open position, and means operable upon the depression of the receiver hook to automatically close said 125 first mentioned switch.

12. In a telephone system, the combina- 130

tion with a plurality of telephone instruments, each including a receiving hook, of a line including sections leading from one instrument to the next, a switch at each instrument normally connecting the line sections and including a swinging switch blade, a spring for normally holding said blade in operative position, a catch for holding said blade in raised position, and means 10 acting between the receiver hook and catch to release the catch upon the depression of the receiver hook.

13. In a telephone system, the combination with a line divided into sections, of a telephone instrument located between adjacent sections, a switch carried by said instrument, the line sections being connected to said switch, a pole changing switch carried by said instrument, conductors connecting the first mentioned switch with the pole changing switch, a transmitting and receiving circuit formed through the pole changing switch, a signaling circuit formed through said pole changing switch, means 25 for holding the first mentioned switch in open position, and means operably by the depression of the receiver hook for automatically closing said first mentioned switch.

14. In a telephone system, the combination with a plurality of telephone instruments, each including a receiver, a transmitter, a signaling mechanism and a calling mechanism, of a line including sections leading from one instrument to the next, means 30 included in each section and independent of the instrument for connecting the receiver, transmitter and calling mechanism in circuit with one section of the line, and the signaling mechanism in circuit with the opposite section or all in circuit with both sections.

15. In a telephone system, the combination with a plurality of telephone instru-

ments, each including a receiver, a transmitter, a signaling mechanism and a calling mechanism, of a line including sections leading from one instrument to the next, means for selectively connecting the receiver and transmitter in circuit with either line section, the calling mechanism being included in said circuit, and means for connecting the signaling mechanism in circuit with the opposite line section or the receiver, transmitter and signaling mechanism all in circuit with both sections.

16. In a telephone system, the combination with a line divided into sections, of a telephone instrument located between adjacent sections and including a transmitter, a receiver, a receiver hook a signaling mechanism and a calling mechanism, all normally in circuit with both sections when the receiver hook is free, and means for opening the circuit to put the transmitter, receiver, and the calling mechanism in circuit with one of said sections and the signaling mechanism in circuit with the other section.

17. In a telephone system, the combination with a line divided into sections, of a telephone instrument located between adjacent sections and including a transmitter, a receiver, and a calling mechanism, all in branches of one circuit, and a signaling mechanism in another circuit, and means for selectively connecting either of said circuits with either of the line sections and the other circuit with the remaining line section or both circuits with both line sections.

In testimony whereof I affix my signature in presence of two witnesses.

FRANK EZRA SUMMERS. [I. S.]
